UNITED STATES PATENT OFFICE.

ROY M. STRONG, OF PLATTEVILLE, WISCONSIN.

DEVICE FOR HOLDING OILCLOTH.

1,366,608.

Specification of Letters Patent. Patented Jan. 25, 1921.

Application filed May 1, 1920. Serial No. 373,267.

To all whom it may concern:

Be it known that I, ROY M. STRONG, a citizen of the United States, residing at Platteville, in the county of Grant and State 5 of Wisconsin, have invented certain new and useful Improvements in Devices for Holding Oilcloth; and I do hereby declare the following to be a full, clear, and exact description of the invention, such as will enable others skilled in the art to which it 10 appertains to make and use the same, reference being had to the accompanying drawings, and to the letters and figures of reference marked thereon, which form a part 15 of this specification.

This invention relates to dispensing, and particularly to an apparatus for dispensing oil cloth, wall paper and the like. An object of this invention is to provide a plurality 20 of reels concentrically mounted whereby the same may be interchanged and the desired reel of oilcloth or wall paper or other similar article to be dispensed may be interchanged and paid out over a table and metered upon that table, and to provide an improved device of this class. A further object to this invention is to provide a squirrel cage arrangement of a plurality of reels which may be quickly supplied with the roll 25 30 of the desired article to be dispensed and to provide an improved means of mounting these rolls upon the master reel carrier. A further object of this invention is to provide an improved means of guiding and retaining the material to be dispensed upon its reel. A further object of this invention is to 35 generally improve the structure of reels of this character.

These and other objects in view of the invention consist in the construction, the combination, the details, and the arrangement of parts as hereinafter more fully described and claimed.

In the drawings:

Figure 1 is a front elevation of this device.

Fig. 2 is an end elevation.

Fig. 3 is a section at 3—3 of Fig. 1.

Fig. 4 is a fragmentary section at 4—4 of

Fig. 2.

The embodiment of my invention provides a pair of standards perforated at 3 to journal a shaft hereinafter more fully described and perforated at 4 and 4¹ to receive rods 5 and 5¹ and also perforated at 6 and 7 to receive cross rods 8 and 9, there being

mounted on cross rods 8 and 9 a yoke bar 10, the rod 5¹ passing through perforations 11 and 11¹ in said yoke bar whereby the said yoke bar 10 is fixedly held and forms a 60 socket for a brace rod 12, which brace rod 12 is pivotally mounted to the front of the table at 13, the table being designated by the numeral 14. The table 14 is pivoted at 15 and the brace rod 12 is provided with a 65 hook end 16 so that by its upward movement it may be released from the rod 9 and thereby the table lowered as may be desired. The rods 5¹, 8, 9, and the yoke bar 10 serve as 70 connecting and supporting members for the standards 2 and 2¹. Passing through perforations 3 of the said standards is a shaft 16, to which is fixedly mounted by set screws 17 the pair of disks 18 and 18¹, which disks are spaced apart and held in spaced relation 75 by four rods 19 with nuts 20 and 20¹. Between the rods 19 are similar adjustable rods 21, there being preferably three of these rods between each pair of the said rods 19. The said disks 18 and 18¹ being 80 drilled for a portion of their thickness with holes 22. The perforations 22 are adapted to receive the ends of rods 21 and alternate on each disk with blocks 23, which blocks 23 are adapted to receive the opposite ends 85 of the rods 21 and are so disposed that the alternate rods 21 are inserted from reverse ends of the said device. Pivotally mounted adjacent the said blocks 23 are hooks 24 of suitable structure to retain the said rods 21 90 by the angular movement of the said hooks 24. Integrally formed on the said disks 18 and 18¹ are a series of sockets 25 adapted to receive latchpins 26 mounted in standards 2 and 2¹, the said latchpins being held yieldingly inward by helical springs 27. By 95 means of the said latchpins engaging in the said socket the said disks may be rotated from socket to socket or to the desired socket, thereby placing the said bar 21 in the 100 desired position before the table 14 whereby the roll of oilcloth or other desired material may be paid out on the said table 14. In skeleton as shown at 27 is a reel of oilcloth mounted upon one of the bars 21 and 105 extending at 28 upon the table 14. The table 14 is provided with graduations in inches or other desired denominations as shown at 29 whereby the said material to be dispensed may be metered out as it passes 110 over the said table. Mounted in spaced relation between the said disks 18 and 18¹ is

a spider set of bar springs 29, the same being mounted by rivets or bolts 30 to a disk 31 and being interconnected in pairs by bars 32, which bars 32 serve to guide and retain the material which is dispensed upon the reel and is yieldingly held against the reel by the said springs 29.

What I claim is:

A pair of standards mounting a squirrel cage arrangement of rods for carrying material to be dispensed from rolls, a table pivotally mounted to said standards, a depend-

ing pivoted member mounted to the distal side of said table, a brace rod interconnecting said standard in the path of said depending member, a secondary rod interconnecting said standard, a yoke bar in the path of said depending member having said brace rods passing therethrough and having its end mounted on other of said connecting rods.

In testimony whereof I hereunto affix my signature.

ROY M. STRONG.
